W. H. ~~W. H. H.~~ Richardson
Design for Tea or Coffee Service.

Patented July 4, 1857.

Dec. 657

William Hattersley and
Charles Dickinson, of Newark, N. J.
Letters Patent No. 657 Dated July 4th 1857.

The schedule referred to in these Letters Patent and making part of the same

To all whom it may concern:

Be it known that we, William Hattersley, and Charles Dickinson, of Newark, in the County of Essex, and State of New Jersey, have invented a new and ornamental design for a tea or coffee pot and we do hereby declare that the following is a full, clear, and exact description of the same, reference being had to the accompanying drawings, forming part of this specification, in which

Fig. 1, is a side view of a pot of our design.

Fig. 2, is a vertical section of the same.

Similar letters of reference indicate corresponding parts in both Figs.

The general form of the vessel is that of a vase, and the ornamental work

2

Des. 657

represents the vine with its leaves and fruit. The foot of the vase is surrounded with orn work in bas relief, representing the vine and its leaves. That part of the ornament a, b, which is visible in Fig. 1, is repeated all round. The spout represents a portion of the vine, which is curved in a suitable form, and bears leaves c, c, on either side, and fruit d, hanging below. The handle also represents a portion of the vine, which is forked at e, where its lower part unites with the vase, is extended as though derived of a scion, at f, and has a leaf g, on each side, and a bunch of fruit h, below, where the upper part unites with the vase. On each side of the fullest part of the body of the vase, there is an ornament in bas relief, representing a piece of vine i, bearing leaves i, i, j, j, and k, and fruit l, l, and above the ornament, there is, where the vase is contracted towards the mouth, a leaf m. The lid has an ornament at the top, which represents a piece of vine n, with a bunch of fruit o, and on each side of this, are two leaves p, q, spreading over the lid.

What we claim as our invention and desire to secure by Letters Patent, is

Ex. d. The design and configuration of the ornamental work as herein described, forming a new and original design for a tea or coffee pot.
